UNITED STATES PATENT OFFICE.

WILLIAM J. SCHULTZ, OF MCKEESPORT, PENNSYLVANIA, ASSIGNOR TO FIRTH-STERLING STEEL COMPANY, OF MCKEESPORT, PENNSYLVANIA, A CORPORATION OF PENNSYLVANIA.

TEEMING DEVICE.

1,403,646.

Specification of Letters Patent. Patented Jan. 17, 1922.

Application filed February 18, 1921. Serial No. 446,081.

To all whom it may concern:

Be it known that I, WILLIAM J. SCHULTZ, a citizen of the United States, residing at McKeesport, in the county of Allegheny and State of Pennsylvania, have invented a new and useful Improvement in Teeming Devices, of which the following is a full, clear, and exact description.

The present invention relates to a teeming device and more particularly to a device for teeming crucible pots. In the manufacture of crucible steel, the steel is teemed or poured from the crucible pots into a ladle or other receptacle for further use.

The object of the invention is to produce a teeming device for securely holding the pots during the teeming operation.

In the drawings, which illustrate the preferred embodiment of the invention,

Figure 1 is a front elevation of the device.

Figure 2 is a side elevation, and

Figure 3 is a detail view.

Referring to the illustrated embodiment of the invention, the teeming device indicated generally by reference numeral 2, is mounted on the edge of the usual platform 3 upon which the crucible pots 4 are trundled by hand trucks 5. A casting ladle 6 is located in the pit at the edge of the platform 30 to receive the metal from the crucible pots 4.

The teeming device comprises a tilting holder or cradle 7 mounted on a carriage 8 to be movable longitudinally along the edge of the platform. The carriage 8 has wheels 9 running along a square rail 10. The rail 10 is pivotally mounted at 11 in suitable supports. One end of the rail 10 carries a large gear wheel 12 which meshes with a pinion 13 operated by a hand crank 14. A workman by turning the crank 14 can tilt the teeming device from the full line to the dotted line position shown in Figure 2 to pour the metal. A locking device comprising a bar 15 having a cam 16 engaging the rail 10 is provided to lock the teeming device in position on the rail. A pin 17 holds the locking bar 15 in position. While it is preferred, for convenience, to mount the teeming device on the carriage running longitudinally of the pouring platform, such mounting is not essential.

The crucible pots are retained in the cradle or holder 7 during the teeming operation by means of a retaining device or yoke 18.

This yoke 18 is pivoted at 19 to the top of 55 the cradle or holder 7. It has downwardly extending arms provided with counterweights 20 so that the yoke is gravity operated to embrace or release the crucible pot 4. The counterweights 20 are adjustable along the 60 horizontal extensions 21 of the yoke arms and are held in position by locking screws 22. This is for the purpose of adjusting the weights so as not to interfere with the pot-embracing prongs of the pot trucks 5.

As shown in Figure 2, when the teeming device is upright, the yoke 18 is held above the crucible pot 4 so that a pot may be readily placed in or removed from the cradle 7. When the cradle 7 is tilted to pour the 70 metal, the counterweights 20 throw the yoke 18 around the crucible pot 4 into the position indicated in dotted lines in Figure 2, thus securely retaining the pot during the teeming operation. This pot-retaining yoke 75 does away with the necessity of manually holding the pot from sliding out of the teeming device, as has been the usual practice in steel mills heretofore.

While the invention has been specifically 80 illustrated and described in connection with teeming crucible pots in the steel industry, it is to be understood that the invention is not necessarily so limited but may be employed for teeming other receptacles. The 85 invention is therefore not limited to its illustrated embodiment but may be embodied in other structures within the scope of the following claims.

I claim:

1. A teeming device, comprising a tilting holder for teeming a pot and means thrown into operation during the tilting of the holder for embracing and retaining the pot, substantially as described.

2. A teeming device, comprising a holder for teeming a pot and means thrown into operation automatically when the pot is tilted to retain the pot in the holder during the teeming operation, substantially as described.

3. A teeming device, comprising a tilting holder for teeming a pot and a gravity operated means acting automatically upon the tilting of the holder for retaining the pot 105 therein, substantially as described.

4. A teeming device, comprising a tilting holder for teeming a pot and a counter-

weighted yoke hinged on the holder and thrown around the pot by the tilting movement of the holder, substantially as described.

5. A tilting device, comprising a tilting holder for teeming a pot and a gravity operated yoke normally held above the pot but

arranged to be brought into embracing engagement with the pot by the tilting movement of the holder, substantially as described.

In testimony whereof, I have hereunto set my hand.

WM. J. SCHULTZ.
